UNITED STATES PATENT OFFICE

2,542,735

FAN GUARD MOUNTING

John H. Viewegh, Indianapolis, Ind.

Application May 27, 1948, Serial No. 29,541

1 Claim. (Cl. 330—275)

1
 This invention relates to means for mounting a fan guard upon a motor which drives the fan. A primary object of the invention is to provide mounting means whereby the guard may be mounted on a motor irrespective of its diameter or possible mounting location. In other words the invention resides in providing means for mounting the guard on motors of varying diameters, and particularly of varying diameters of locations of through-bolts. By reason of the peculiar mounting means forming the gist of the invention, the number of different sizes and devices for mounting the guard are reduced to a minimum. While there may be considerable variation in the diameters of motors driving a certain diameter fan, the guard may be mounted on any one of those motors without having to change the guard itself in any respect.

These and other objects and advantages of the invention will become apparent to those versed in the art in the following description of one particular form of the invention as illustrated in the accompanying drawing, in which,

Fig. 1 is a view in front elevation of a structure embodying the invention;

Fig. 2, a view in side elevation; and

Fig. 3, a detail on an enlarged scale in section on the line 3—3 in Fig. 1.

Referring to the drawing, wherein like characters of reference indicated like parts in the several views thereof, the fan guard designated generally by the numeral 10 is made in the usual manner to have primarily on its rear side a pair of circular hoops 11 and 12, the hoop 11 at the rear being of a smaller diameter than is the diameter of the hoop 12 which is spaced forwardly a distance from the hoop 11. In other words the planes of these two hoops 11 and 12 are spaced one from the other, normally in vertical positions.

A plurality of bars, herein shown as being formed of flat bar stock and generally indicated by the numeral 13, four of the bars being employed in the present illustration, are equally spaced one from the other circumferentially around and in interconnecting positions between the hoops 11 and 12. As best indicated in Fig. 3, the outer end of each bar 13 is wrapped around the hoop 12, to form an eye 14 so as to securely grip that hoop 12. The other end portion of the bar 13 is carried across the outer side of the hoop 11 and secured thereto in any suitable manner such as by welding. From the weld position, the end portion of the bar 13 in each instance is

carried inwardly in a plane parallel to the plane of the hoop 11 to form a foot 15.

To each of these feet 15 is rockably secured an arm 16 by any suitable means, such as by a rivet 17 which passes through the foot 15 and through an end portion of the arm 16. Each of these arms 16 extends from the pivot rivet 17 by a straight length and then terminates in an end portion 18 which is turned substantially at right angles to the major length by a finger constituting that end portion 18.

When the guard 10 is mounted to encircle the fan 19 and brought up to the end portion of the motor 20 behind the fan 19, these arms 16 are presented in a manner whereby the major lengths thereof will be substantially tangential to a circumferential portion of the motor 20 and the fingers 18 turned inwardly therefrom toward the motor. As is the case with most fan motors, there are a plurality of bolt ends 21 projecting from the end of the motor, four in number as a rule, to tie together the motor ends 22 and 23 against the cylindrical central member 24 which carries the poles of the motor. Advantage is taken of this fact by engaging the ends of the fingers 18 under nuts 25 carried on these bolts 21. In other words these arms 16 are swung to the position whereby holes provided in the end portions of the fingers 18 will register with and permit the bolts 21 to extend therethrough so that the nuts 25 may be pulled up against the outer faces of these fingers. Therefore it is obvious that these arms 16 may be rocked about their pivot rivets 17 to accommodate the fingers 18 to various diameters of bolt circles which may be encountered on different types of motors. And it is also obvious that the diameter of these bolts may vary considerably and still be within the permissible range for attachment of these fingers 18 to the motor.

While I have herein shown and described my invention in the one particular form, it is obvious that structural changes may be employed without departing from the spirit of the invention, and I therefore do not desire to be limited to that precise form beyond the limitations which may be imposed by the following claim.

I claim:

For a motor having a plurality of securing members circumferentially spaced apart on a circle having its center coincident with the axis of said motor, means for mounting a fan guard having a rear hoop, said means comprising a plurality of circumferentially spaced apart arms 50 rockably secured to said rear hoop to be limited

to swing toward and away from said motor in a plane parallel to said rear hoop; and a finger on each arm directed inwardly at substantially a right angle relative to its respective arm toward said motor for interengagement respectively with one of said securing members, each of said fingers being presented in a common plane parallel to said rear hoop; the lengths of said arms being such that they will be substantially tangential to and entirely outside of said circle when 10 said fingers are engaged with said securing members.

JOHN H. VIEWEGH.
